UNITED STATES PATENT OFFICE

2,440,522

STOP FOR DIAL INDICATORS

Clarence S. Ost, Atlantic City, N. J.

Application August 14, 1946, Serial No. 690,452

1 Claim. (Cl. 74—526)

1

My invention relates to new and useful improvements in stops or pre-set selector mechanisms for dial indicators, and has for an object to provide a simple and inexpensive mechanism that may be readily applied to different general forms of electrical or mechanical timers, etc., wherein it is especially desired to repeat the operation by re-setting a pointer or indicator.

Another object of the invention is to provide a stop or re-set mechanism that is secured partly in front and partly behind the dial face. Then that part of the stop mechanism that is mounted in front of the dial face may be quickly and readily set to any desired position and locked with a twist of a knob.

Still another object of the invention is to provide an extremely simple stop that may be very accurately positioned and then locked against movement until it is desired to re-set the same.

With these and other objects in view, the invention consists in certain new and novel constructions and combination of parts as will be hereinafter more fully described and pointed out in the claim.

Referring now to the drawings showing a preferred embodiment,

Fig. 1 is a front face view showing fragmentarily a dial with an indicator and a stop mechanism locked in position,

Fig. 2 is a side elevation of the same,

Fig. 3 is a rear view,

Fig. 4 is an enlarged sectional view taken on line 4—4 of Fig. 1, and

Fig. 5 is a fragmentary sectional view taken on line 5—5 of Fig. 1.

It will be understood that this stop or re-set indicator may be applied to the face plate or dial of numerous forms of mechanical, electrical or electronic instruments wherein an indicator hand or pointer is to be turned to a set position, and then moves in an anti-clockwise direction until its cycle is completed, after which the indicator finger is again to be set up against the stop to repeat the operation.

Referring now to the drawings, and for the moment to Fig. 1, there is shown the face plate 1 of a timer 2, and on this face plate 1 is shown the dial 3, which is calibrated as at 4, in any desired number of divisions. It so happens that in the timer to which the present stop is applied there are two hundred divisions.

Centrally of the dial 3 is an aperture 5 through which extends a sleeve 6 that is soldered or otherwise fastened to the rear face of the stop arm 7, while at the end of the sleeve 6 is the relatively

2

large, soldered, or otherwise fastened, flat circular plate 8, as may be seen in Fig. 3, which is substantially the same size or larger than the dial 3. At the outer end of the arm 7 is a small post 9, against which an indicator or pointer, later to be mentioned, is to be positioned, as will also be later mentioned.

In the present instance, the plate 8 is slightly cut out and turned up on its periphery to form a lug 10 on the rear of the plate 8.

Referring to Figs. 3 and 5, there will be seen the clamping arm 11, which is riveted as at 12 to the rear of the plate 1, there being a small spacing washer 13 between the plate 1 and the arm 11, while the outer end of the arm 11 overlies the periphery of the plate 8.

Thus when the plate 8 is revolved in an anti-clockwise direction from the position shown in Fig. 3, the lug 10 will contact with the arm 11, and the arm 7 on the front of the face plate 1 with its post 9 would be nearly opposite the graduation ten (10) in Fig. 1.

In the present embodiment, the arm 7 can not be set closer to the zero point than the graduation ten (10) as the timer is constructed in this manner. However, in many instances it would not be necessary to have this lug 10, and the plate 1 could revolve three hundred sixty (360°) degrees.

30 Securely fastened to the clamping arm 11 is the threaded post 14 which extends through the face plate 1 and over which may be placed a small fiber washer 15, while fitted on the post 14 is a small threaded knob 16, so that when this knob 16 is turned down it will pull the clamping arm 11 tightly against the plate 8 and in turn hold it against the rear of the face plate 1 to hold the plate 8 from a turning movement even if the arm 7 were tried to be moved by the user.

40 As far as the specification has proceeded, therefore, it will be understood that there is an arm 7 on the face of the dial 3 with an upright post 9 at its outer end, while fastened to the arm 7 is the sleeve 6 which passes through the aperture

45 5 in the face plate 1 and has its other end fastened to the flat metal disk 8, which is to be locked or unlocked by a slight turn of the knob 16 to either clamp or release the plate 8 against the back of the plate 1. This in turn will either 50 clamp the arm 7 in position relative to a chosen division on the dial or release the arm 7 so that its position may be changed.

Now, referring to Fig. 1, there will be seen a handle 17 with its set screw 18 in the rear thereof so that this handle 17 may be locked to a

post 19 that passes through the sleeve 6 which is fitted in the central aperture 5 in the dial face 3 and sets the mechanism (not shown) in the timer. This handle 17 has a pointer or indicator 20, and in Fig. 1 it will be seen abutting against the post 9. In fact, the post 9 is slightly undercut as at 21 as may be seen in Figs 1 and 2.

Also, as may be seen in Fig. 1, there is a small stop 22 just below the zero point on the dial face 3, so the pointer 20 will not be turned when setting in a wrong direction.

The operation of the device is as follows: Supposing the timing mechanism is to operate for the period of time that it takes the pointer 20, set at the graduation thirty (30) to work back to the zero point, and this is to be repeated, we will say, a number of times.

First, if the knob 16 were tight, it would be loosened to release the clamping arm 11, and the pointer arm 20 would be set at the numeral thirty (30), and the small post 9 on the arm 7 grasped with the fingers and the arm 7 moved until the post 9 contacts with the pointer 20.

Of course, another way to set the stop would be to simply loosen the small knob 16 and then turn the handle 17 and turn the pointer 20 to the desired graduation, this pointer 20 in turn pushing the arm 7 and its post 9 ahead of it, and after the pointer 20 is at the desired graduation, then the disk 8 will again be locked by turning the knob 16.

After the mechanism (not shown) is started and the pointer 20 works back to the zero point, the mechanism (not shown) will be cut off; but to re-set it, it is only necessary to grasp the handle 17 and turn it in a clockwise direction until the pointer arm 20 again contacts with the post 9.

Thus, the operator does not have to look closely, each time at the graduations when the pointer arm 20 is to be set at, say thirty; as, in order to repeat, he simply turns the handle 17 until the pointer arm 20 contacts with the pre-set post 9.

This is of great advantage when working in the dark room or a subdued light, or when the same setting is to be repeated many times.

By making the re-set or stop as above explained, it will be seen that the pointer 20 can be accurately set to any of the graduations desired, in fact, even between the graduations if so desired.

For a new setting of the arm 7 it is only necessary to unloosen the arm 11 by turning the knob 16, push the post 9 on the arm 7 against the pointer 20, and then turn the pointer 20 to any desired graduation which will force the post 9 ahead of it, after which the knob 16 may again be turned to lock the plate 8 and its arm 7 in position.

From the foregoing, it will be seen that I have provided a stop or re-set mechanism that is cheap to manufacture, readily assembled, and may be set with great accuracy. It also saves considerable time where there are a number of repeat operations to be made.

Having thus described my invention, what I claim is new and desire to secure by Letters Patent is:

In a stop for dial indicators in combination with a face plate having a dial thereon, a rotatable arm on the front of the face plate, an upstanding post at the outer end of said arm, a relatively large rotatable disk on the back of the face plate secured to said arm, operable means extending through the face plate for clamping the disk to the rear of the face plate in any selected rotated position to thereby also lock the arm on the front of the face plate in a desired selected position, a pointer arm adapted to be limited in its reset position by the said post on said arm, and means on the said disk for limiting the movement of said first mentioned arm.
